WAVEGUIDE TO COAXIAL TRANSMISSION LINE TRANSITION

Edwin S. Lewis, Merchantville, and Eric A. Thowless, Marlton, N.J., assignors, by mesne assignments, to the United States of America as represented by the Secretary of the Navy

Application October 8, 1957, Serial No. 689,021

1 Claim. (Cl. 333—98)

This invention relates to wide-band microwave transmission systems and more particularly to a novel coupling arrangement for joining a rectangular waveguide to a coaxial transmission line.

When a rectangular waveguide and a coaxial transmission line are coupled together to form a microwave transition, the center conductor of the coaxial line extends into a cavity within the waveguide. If the waveguide is excited with radio frequency energy in the microwave region, this energy will cause an electric field to be set up in the cavity. This field will in turn excite a TEM mode in the coaxial line.

If the center conductor of the coaxial line is not accurately centered within the waveguide cavity, undesired modes may be set up which cannot propagate in the coaxial line. Any undesirable mode set up in this way will be trapped in the cavity. At a frequency at which the cavity is resonant to the trapped energy, a high voltage standing wave ratio (VSWR) results, looking into the cavity from either the coaxial line or from the waveguide. The magnitude of the VSWR and the frequency band over which it exists depends on the amount of excitation of the undesirable mode caused by the non-symmetrical structure and the Q of the cavity. The VSWR is usually at a maximum over a very narrow range of frequencies generally occurring about the midpoint of the frequency band which may be transmitted through the waveguide and coaxial line.

The undesirable mode can be minimized by using extreme care in manufacture to accurately, to a very small tolerance, center the center conductor in the cavity within the waveguide. This, however, results in higher manufacturing costs. The problem is particularly acute when a waveguide to coaxial transition is used in a rotary joint. In such a joint, some looseness is needed for easy turning, and also rotation of the center conductor accentuates the non-symmetrical effects.

It is an object of this invention to provide a waveguide to coaxial transition wherein such extreme care in manufacture is not required.

Another object of this invention is to provide a waveguide to coaxial transition in which the VSWR is minimized despite non-symmetry in the transition.

A third object of this invention is to provide a waveguide to coaxial transition which is economical to manufacture.

Another object of this invention is to provide a waveguide to coaxial transition particularly suitable for use in a rotary joint and in which rotation of the center conductor of the coaxial line will not accentuate non-symmetrical effects.

This invention accomplishes these objects by providing a means for absorbing or suppressing undesired modes in the cavity of a waveguide to coaxial transition. The transition comprises a coaxial transmission line whose outer conductor is electrically connected to one wall of a waveguide while the center conductor extends within the waveguide. The center conductor is terminated in

2

a conical conductive member tapering outward as it approaches the wall opposite from the conductor's entrance into the waveguide. A plurality of small buttons of lossy material are located on the inner side of the waveguide wall adjacent to the base of the conductive cone. Any undesired modes caused by non-symmetry in the structure of the transition are substantially attenuated by the buttons of lossy material while the desired mode is virtually unaffected.

10 Other objects and many of the attendant advantages of this invention will be readily appreciated as the same becomes better understood by reference to the following detailed description when considered in connection with the accompanying drawings wherein:

15 Fig. 1 is a side view of a waveguide rotary joint broken away to show in cross section the waveguide to coaxial transition of this invention;

20 Fig. 2 is a cross-sectional view taken along the line 2—2 of Fig. 1 and a schematic illustration of an undesirable mode set up in the transition; and

25 Fig. 3 is similar to Fig. 2 and taken along the same line, but shows the proper TE mode set up in the transition.

30 The rotary joint shown in Fig. 1 is designed to couple together a rectangular waveguide 11 and coaxial transmission line 12. Various bearings and housing members are required to support the rotary joint. Since these are entirely of conventional design and form no part of this invention details thereof have been omitted, and the housing is generally represented in cross section by the box 13.

35 In coupling the waveguide 11 to the coaxial line 12 to form the transition of this invention, the outer conductor 14 of the coaxial line is physically and electrically joined to the top wall 15 of the waveguide through a conventional choke section 16. To facilitate broadband operation the outer conductor 14 is tapered outwardly adjacent to its junction with the top wall 15 of the waveguide 11. The inner conductor 17 of the coaxial line extends into the waveguide 11 to the opposite or bottom wall 18. Support means for the coaxial inner conductor is provided as shown; this comprises: a graphited-bronze bearing 19 in which the end of the inner conductor 17 is seated and which in turn is seated in a metallic bushing support 20. In the form shown the side walls 24, Fig. 2, are spaced at least one-half wavelength apart. A broadband matching member 21 of conductive material is provided which has a shaped surface projected upward from and electrically connected to the bottom wall 18 of the waveguide. It is this surface which provides the broadband matching function. The base portion of this matching member 21 forms a part of the supporting means for the inner conductor of the coaxial transmission line 12. Specifically illustrated is a conically shaped matching member 21 which projects inward through the bottom wall 18 of the waveguide 11 and surrounds the end of the inner conductor 17. The space between the matching member 21 and the inner conductor 17 and also between the matching member 21 and the bushing support 20 provides an RF choke for the inner conductor 17. As is common with rotary joints of this type the waveguide 11 is provided with a broadband matching iris 22.

40 45 50 55 60 65 When a rotary joint was constructed in the manner thus far described, it was found that satisfactory performance could not be obtained. RF energy transmitted by the waveguide 11 to the waveguide to coaxial transition caused improper modes to be set up in the transition which could not be propagated in the coaxial line 12 for transmission to the radar receiver. The same was true

70 when attempting to transmit RF energy in the reverse

direction from the transmitter through the rotary joint to the antenna. The improper or undesirable modes produced a VSWR as high as 1.8 which meant that approximately 8% of the energy injected into the transition in either direction was being reflected. These undesirable modes are illustrated by the arrows 23 in Fig. 2. Though illustrated separately in Fig. 2 it should be clearly understood that in fact they occur simultaneously with the desired mode which is illustrated by the arrows 25 in Fig. 3. It was found that they were caused by eccentricities in the coupling of the waveguide 11 and the coaxial line 12. Rotation of the waveguide 11 from one position to another relative to the coaxial line varied the strength of these undesirable modes so as to accentuate unsatisfactory performance. Continued efforts to improve performance by the exercise of greater skill in manufacturing were met with failure. Attention was next centered on devising means to attenuate the undesirable modes without simultaneously attenuating the desirable TE mode. Mode suppressors were designed with various geometrical configurations and were made from many different materials. Materials such as resistance cards, powdered iron, and carbon impregnated substances were employed. Attempts were made to attenuate the undesirable modes by affixing the various suppressors to the side walls 24 as well as the bottom wall 18 of the waveguide cavity. Every attempt resulted in failure—the desired TE mode was attenuated as well as the undesired modes—until the mode suppressors described below were employed.

In Fig. 3 the arrows 25 illustrate a desirable TE mode which will propagate in the coaxial line 12. This result was finally attained by positioning two buttons 26 of lossy material, one on each side of the conductive member 21 on the bottom wall 18 of the waveguide 11. Excellent performance was obtained by employing buttons having a diameter of $\frac{1}{4}$ inch and a height of $\frac{1}{8}$ inch. It was found that the VSWR was reduced from the previous figure of 1.8 to a ratio of 1.1. This meant that instead of 8% of the energy being reflected, the use of the buttons 26 so improved performance that only $\frac{1}{4}$ of 1% was reflected at the resonant frequency. The size of the buttons employed in such a waveguide to coaxial transition will vary depending upon the dimensions of the transition, the RF frequency of the energy to be transmitted therethrough, the Q of the cavity, and the magnitude of the asymmetry in the waveguide to coaxial line coupling. In general such buttons should have a diameter not greater than one-tenth of a wave length and a height not greater than one-twentieth of a wave length. The buttons 26 may be square or of some configuration

other than round without detracting from their function. One example of a lossy button material which was found satisfactory was carbon loaded Bakelite, known by the trade name of "Synthane." When buttons of this material and of the size mentioned above were employed in a waveguide coaxial transition, it was found that undesirable modes were more than adequately attenuated while the desired TE mode was virtually unaffected.

Obviously many modifications and variations of the present invention are possible in the light of the above teachings. It is therefore to be understood that within the scope of the appended claim the invention may be practiced otherwise than as specifically described.

What is claimed is:

- 15 In a broadband microwave transmission system a waveguide rotary joint comprising in combination a rectangular waveguide, the end, side, top and bottom walls of one end of said waveguide enclosing a resonant cavity, said side walls being spaced apart a distance at least equal to one-half of one wave length, an aperture in said top wall providing an entrance into said cavity, a coaxial transmission line having an outer conductor coupled to said top wall and an inner conductor projecting into said cavity through said aperture, said outer conductor being 20 uniformly tapered outward to mate with said aperture in said top wall, a graphited-bronze bearing into which the end of said inner conductor is seated within said cavity, a cylindrical metallic support for said bearing, a conically shaped conductive member surrounding said 25 30 end of said inner conductor and said metallic support, the base of said member being affixed to said bottom wall, a pair of mode suppressors affixed to said bottom wall on opposite sides of said conical member, each of said mode suppressors being located substantially midway between said conical member and one of said side walls, each said mode suppressor comprising carbon-loaded Bakelite material and having a diameter not in excess of one-tenth of one wave length and a height not in excess of one-twentieth of one wave length, said rectangular 35 40 waveguide including a broadband matching iris positioned therein opposite said end wall, and said outer conductor including a rotary radio-frequency choke section.
